CLAIM

The ornamental design for a pillow, as shown and described.

DESCRIPTION

FIG. 1 is a front perspective view of the pillow;
FIG. 2 is a rear perspective view of the embodiment in FIG.
1;

FIG. 3 is a top view of the embodiment in FIG. 1;
FIG. 4 is a right side view of the embodiment in FIG. 1;
FIG. 5 is a front view of the embodiment in FIG. 1;
FIG. 6 is a left side view of the embodiment in FIG. 1;
FIG. 7 is a rear view of the embodiment in FIG. 1; and,
FIG. 8 is a bottom view of the embodiment in FIG. 1.

The broken lines shown in the drawings are included for the
purpose of illustrating unclaimed portions of the pillow and
form no part of the claimed design.

1 Claim, 3 Drawing Sheets
